US0D1023645S

(12) United States Design Patent (10) Patent No.: US D1,023,645 S
(45) Date of Patent:  Apr. 23, 2024

(54) Fixture

(71) Applicant: Target Brands, Inc., Minneapolis, MN (US)

(72) Inventors: Jennifer A. Theisen, Crystal, MN (US); William Y. Stafford, Minnetrista, MN (US); Benjamin S. Weshler, New York, NY (US); Marc D. Weshler, Port Washington, NY (US)

(73) Assignee: Target Brands, Inc., Minneapolis, MN (US)

() Term: 15 Years

(21) Appl. No.: 29/810,269

(22) Filed: Oct. 4, 2021

(51) LOC (14) Cl. 06-04

(52) U.S. Cl.

USPC D6/675

(57) CLAIM

The ornamental design for a fixture, as shown and described.

DESCRIPTION

FIG. 1 is a perspective view of a fixture showing our new design with environment;

FIG. 2 is a left side view thereof;

FIG. 3 is a right side view thereof;

FIG. 4 is a front view thereof; and,

FIG. 5 is a top view thereof.

The broken lines are included for purposes of illustrating environment or portions of the fixture and form no part of the claimed design.

1 Claim, 5 Drawing Sheets
